Henry C. Klagges, Collingswood, N. J., and Harold E. Steinberg, Philadelphia, Pa., assignors to The Esterbrook Pen Company, Camden, N. J., a corporation of New Jersey

Application December 27, 1947, Serial No. 143,378

Term of patent 14 years

(Cl. D74—8)

To all whom it may concern:

Be it known that we, Henry C. Klagges (1) and Harold E. Steinberg (2), citizens of the United States of America and residents (1) of Collingswood, Camden County, New Jersey, and (2) of Philadelphia, Pennsylvania, have invented the new, original, and ornamental Design for a Desk Inkwell Unit, of which the following is a specification, reference being had to the accompanying drawing, forming part thereof, in which:

Figure 1 is a perspective view of a desk inkwell unit, showing our new design;

Fig. 2 is a top plan view thereof, and

Fig. 3 is a side elevational view thereof taken in the direction of the arrow of Fig. 2.

We claim:

The ornamental design for a desk inkwell unit, substantially as shown.

HENRY C. KLAGGES.
HAROLD E. STEINBERG.
